DESIGN FOR A COMBINED FINGERNAIL FILE AND POWDER SCOOP

Russell C. Buffum, New York, N. Y., assignor to
Graef & Schmidt, Inc., New York, N. Y., a
corporation of New York

Application February 7, 1940, Serial No. 90,088

Term of patent 3½ years

To all whom it may concern:

Be it known that I, Russell C. Buffum, a citizen of the United States and residing at New York city, in the county and State of New York, have invented a new, original, and ornamental Design for a Combined Fingernail File and Powder Scoop, of which the following is a specification, reference being had to the accompanying drawing, forming part thereof.

In the drawing:

Figure 1 is a top plan view of a combined fingernail file and powder scoop showing my new design;
Figure 2 is a side elevational view thereof;
Figure 3 is a bottom plan view thereof; and
Figure 4 is a sectional view on lines 4—4 of Figure 3.

I claim:

The ornamental design for a combined fingernail file and powder scoop, substantially as shown.

RUSSELL C. BUFFUM.
